UNITED STATES PATENT OFFICE.

FREDERICK J. HUMPHREY AND HUBERT R. HUMPHREY, OF KALAMAZOO, MICHIGAN,
ASSIGNORS TO GENERAL GAS LIGHT COMPANY, OF KALAMAZOO, MICHIGAN.

VALVE MECHANISM FOR GAS-LAMPS.

1,082,954.

Specification of Letters Patent. Patented Dec. 30, 1913.

Original application filed February 15, 1911, Serial No. 608,695. Divided and this application filed December 16, 1912. Serial No. 737,107.

To all whom it may concern:

Be it known that we, FREDERICK J. HUMPHREY and HUBERT R. HUMPHREY, citizens of the United States, residing at Kalamazoo, Michigan, have invented certain new and useful Improvements in Valve Mechanism for Gas-Lamps, of which the following is a specification.

This invention relates to improvements in 10 valve mechanism for gas lamps.

Our improvements are particularly designed and adapted by us for use in gas lamps of the type illustrated in our application for Letters Patent filed February 15, 15 1911, Serial Number 608,695, of which application the present is a division. Our improved valve mechanism is, however, readily adapted and desirable for use in other structures.

20 The main objects of this invention are: First, to provide an improved valve mechanism by which the pilot is flashed upon the actuation of the mechanism to open and close the main valve. Second, to provide an 25 improved valve mechanism which is comparatively simple and economical in structure and easily operated and not likely to get out of repair or adjustment in use.

Further objects, and objects relating to 30 structural details, will definitely appear from the detailed description to follow.

We accomplish the objects of our invention by the devices and means described in the following specification.

35 The invention is clearly defined and pointed out in the claims.

A structure which is a preferred embodiment of our invention is clearly illustrated in the accompanying drawing forming a 40 part of this specification, in which:

Figure I is a side elevation of a gas lamp embodying the features of our invention. Fig. II is an enlarged detail, mainly in vertical section, through the main burner valve. Fig. 45 III is an enlarged detail partially in vertical section, through the pilot valve. Fig. IV is an end view of the valve mechanism, the movement of the valve levers being indicated by dotted lines. Fig. V is a detail perspective 50 of the valve stem, the ratchet member 15 and index member 17 thereon. Fig. VI is a detail side elevation of a modified construction embodying the features of our inven-

tion. Fig. VII is a detail view mainly in vertical section, through the valve casing of 55 the modified structure shown in Fig. IV. Fig. VIII is a detail side elevation with the chimney casing removed, looking from the left of Fig. VI. Fig. IX is an enlarged detail elevation of the valve mechanism looking from the right of Fig. VIII.

In the drawing similar reference characters refer to similar parts throughout the several views, and the sectional views are taken looking in the direction of the little 65 arrows at the ends of the section lines.

Referring to the drawing, 1 represents the gas supply pipe; 2 the lamp casing, and 3 the chimney flues. The valve casing 4 is mounted upon the supply pipe coupling 5 70 by means of the screw 6 substantially as described in our said application for Letters Patent.

As the details of the burner form no part of the present invention, we do not describe 75 the same herein.

The main gas valve 7 is of the rotary type and controls the delivery of gas through the 80 passage 8 in the valve casing 4 to the nozzle 9. The valve casing is provided with a passage 10 for the pilot 11 which is controlled by the valve 12. The valve 12 is threaded into the valve casing, the valve being of the needle type and coacting with the valve seat 13 as shown in Fig. III.

The main burner 7 is provided with a projecting valve stem 14 on which the ratchet disk 15 is secured by means of the screw 16 tapped into the end of the stem. This screw also screws the index member 17 to the valve 90 stem.

The actuating lever 18 is rotatably mounted upon the stem 14 and provided with a disk-like ratchet member 19. These ratchet members 15 and 19 are substantial duplicates and are formed of sheet steel or the like, the ratchet teeth 20 being struck laterally therefrom. There are four teeth on these members so that the valve is given a quarter turn at each actuation, one turn 100 opening, the next closing the valve, or vice versa. These ratchet members are held in yielding engagement and the lever 18 is returned to its initial position by means of the coiled spring 21 arranged on the valve stem. 105 At one end the coiled spring is provided

with an arm 22 secured to the stop pin 23 projecting from the valve casing, while the arm 24 at the other end of the spring is secured to the pin 25 projecting inwardly from the lever 18. The spring thus performs the double function of returning the lever to its initial position and also holding the ratchet members yieldingly in engagement. The lever 18 is supported in its initial position by the spring 21 against the stop pin 23. The projection 29 on the lever engages this pin to limit the stroke of the lever.

An arm 26 is adjustably mounted upon the pilot valve 12, the valve being threaded through the arm. The arm 26 has a longitudinal slot 27 therein with which the pin 25 on the actuating lever 18 engages. By thus connecting the parts, the pilot valve is actuated to flash the pilot when the actuating lever 18 is actuated and is closed by the return pilot lever through its return spring 21, so that the pilot is flashed at each actuation whether the actuation is the burner valve closing or opening movement. The pilot remains flashed only so long as the actuating lever is held in its actuated position. The pilot is positively operated to flash the same and to cut off the additional or flashing supply and can be regulated to adjust the amount of the flashing supply. This flashing on both the opening and closing of the main burner is of advantage as the pilot is relighted in the event of its having been extinguished as by an explosion of the main burner or from some other cause, while the burners are lighted. As it is turned with an extra or flashing supply of gas when the burners are cut off, it will be relighted from the burners before they are extinguished. This is of decided advantage as it insures the pilot being lighted when it is cut off from the main burners.

In the modification shown in Figs. VI to IX, our improvements are adapted to a structure in which the main valve 7 is positioned transversely of the position in which it is shown in Figs. I to V, the same being merely an adaptation of the structure previously described. In this construction, owing to the positioning of the pilot valve 12 above the main valve 7, the pilot valve arm 26 is connected to the actuating lever 17 by means of the link 28 instead of the pin and slot connection of the structure shown in detail in Fig. IV, the link being mounted on the pin 25 on the actuating lever. The operation of the device is the same as that of the construction described and we have illustrated this modification herein merely to show an embodiment in which we have used our improved valve mechanism.

The parts of our improved valve mechanism are simple in structure and easily assembled.

Having thus described our invention, what we claim is new and desire to secure by Letters Patent is:

1. In a gas lamp, the combination with a main burner, a pilot burner, a valve casing, a rotary main valve, a pilot flashing and regulating valve threaded into said casing for actuation, said valves being arranged parallel, a slotted arm having threaded engagement with said pilot valve whereby the valve may be adjusted relative to the arm, an actuating lever rotatably mounted on said main valve and provided with a pin engaging the slot of said arm on said pilot valve, a ratchet member secured to said main valve, a ratchet member secured to said lever and coacting with said ratchet member secured to said main valve, and a coiled spring arranged on said main valve and connected at one end to said actuating lever to return the same to its normal position and arranged to hold said ratchet members in yielding engagement. 70 75 80 85

2. In a gas lamp, the combination with a main burner, a pilot burner, a valve casing, a rotary main valve, a pilot flashing and regulating valve threaded into said casing for actuation, said valves being arranged parallel, a slotted arm having threaded engagement with said pilot valve whereby the valve may be adjusted relative to the arm, an actuating lever rotatably mounted on said main valve and provided with a pin engaging the slot of said arm on said pilot valve, a ratchet member secured to said main valve, a ratchet member secured to said lever and coacting with said ratchet member secured to said main valve, and a coiled spring arranged on said main valve and connected at one end to said actuating lever to return the same to its normal position and arranged to hold said ratchet members in yielding engagement. 90 95 100

3. In a gas lamp, the combination with a main burner, a pilot burner, a valve casing, a rotary main valve, a screw threaded pilot flashing and regulating valve threaded into said casing for actuation, an arm having threaded engagement with said pilot valve whereby the valve may be adjusted relative to the arm, an actuating lever rotatably mounted on said main valve and having operative connection with said arm, a ratchet member secured to said main valve, a ratchet member secured to said lever and coacting with said ratchet member secured to said main valve, and a coiled spring arranged on said main valve and connected at one end to said actuating lever to return the same to its normal position and arranged to hold said ratchet members in yielding engagement. 105 110 115 120

4. In a gas lamp, the combination with a main burner, a pilot burner, a valve casing, a rotary main valve, a pilot flashing valve, a slotted arm on said pilot valve, an actuating lever rotatably mounted on said main valve and provided with a ratchet member, a ratchet member with which said ratchet member on said lever coacts secured to said main valve, a coiled spring arranged on said 125 130

main valve, a stop pin for said lever to which one end of said spring is secured, and a pin on said lever to which the other end of said spring is secured, whereby said lever is returned to its initial position and said ratchet members held in yielding engagement, said pin being engaged in said slotted arm of said pilot valve.

5. In a gas lamp, the combination with a main burner, a pilot burner, a valve casing, a rotary main valve, a pilot flashing valve, an actuating lever having operative connections with said pilot valve, said lever being rotatably mounted on said main valve and 10 provided with a ratchet member, a ratchet member with which said ratchet member on said lever coacts secured to said main valve, a coiled spring arranged on said main valve,

a stop pin for said lever to which one end of said spring is secured, and a pin on said lever to which the other end of said spring is secured, whereby said lever is returned to its initial position and said ratchet members held in yielding engagement.

15 In witness whereof we have hereunto set our hands in the presence of two witnesses.
